UNITED STATES PATENT OFFICE.

WARREN POTTS, OF ELKHART, INDIANA.

CHANDELIER.

1,088,722.

Specification of Letters Patent.

Patented Mar. 3, 1914.

Application filed June 18, 1913. Serial No. 774,494.

To all whom it may concern:

Be it known that I, WARREN POTTS, a citizen of the United States, residing at Elkhart, in the county of Elkhart and State of Indiana, have invented a new and useful Improvement in Chandeliers, of which the following is a specification.

My invention relates to that class of chandeliers which are constructed to be adjustable vertically at will.

One of the objects of my invention is to construct a chandelier with improved means whereby a vertical adjustment of the chandelier can be obtained, and at the same time, provide means to prevent the escape of gas from the tubes into the room.

A further object of my invention is to provide a chandelier having electric conductors with extensible casings and suitable means whereby the electric current may be supplied and controlled independently of the vertical position of the chandelier; also in the preferred embodiment, to provide telescoping conductors for this purpose.

A still further object of my invention is to construct the chandelier so that it may be converted into an electric fixture without changing the construction of the parts in which the features of the invention reside.

A still further object of my invention is to provide the vertically adjustable tubes with means for holding them in any position of adjustment.

For the purpose of illustration my invention is shown in the accompanying drawings applied to that type of chandelier adapted to hang from the ceiling, and one in which the electric current is adapted merely for igniting illuminating gas, but it will be obvious that the several features of construction might be applied to a chandelier extensibly supported from a wall; or one in which the electrical conductors serve to supply electric lamps.

In said drawings:—Figure 1 is an elevation of the entire chandelier showing the lamps in contracted position, in full lines; and in extended position in dotted lines; Fig. 2 is an enlarged section of the supporting ports.

Referring to the drawing in detail, 1 designates a supply pipe for illuminating gas, projecting from the ceiling of a room, and having threaded thereto the chandelier gas pipe 1^a, threaded through the upper head of and incased in a permanently fixed casing 2

projecting through the lower head of said fixed casing and partially inclosed thereby is a distributing tube or casing 3, adapted to telescope with the gas pipe 1^a and the outer casing 2, and also adapted to carry suitable stuffing boxes 4 and 5, which provide a double barrier against the escape of gas into the room. Mounted on the outside of the distributing tube 3 are bosses 6 adapted to abut against the lower head of outer casing 2 to limit the extension of the chandelier. Projecting radially from and located at longitudinally spaced points upon the casing 2 are pairs of arms 7 which support the extensible conductor casings 8, 9, and brace them against torsional displacement relatively to the central tube member. The lower ends of these conductor casings are suitably connected to arms 15 of the lamp bracket, and thereby prevent rotation of the bracket.

10 designates the electric conductors rendered extensible, preferably by forming each of them in two telescoping parts, secured, 80 one in the casing member 8, and the other at the lower end of the lower casing member 9. For convenience in wiring the conductors carry binding posts 11 at their respective ends. The members of each extensible conductor casing are provided with inside layers of insulating material 12, 13 to insulate the casing members one from the other and from the conductor. As suggested at 14, any suitable friction grip may be provided 90 at the lower end of the upper casing 8 for the purpose of holding the extension at any vertical adjustment. Mounted on the outer ends of the lamp brackets 15 are other conductor casings 16 which are also adapted to 95 carry conducting rods 17, which are constructed with binding posts 18 to connect the conducting wires 19. For the purpose of ornamentation, 20 designates a canopy which surrounds the gas supply pipe 1 and 100 the upper end of the casing 2, and 21 designates a shell which surrounds the lower end of the distributing gas tube and the inner ends of the lamp brackets 15.

I claim:—

1. In a chandelier, the combination of fixed and telescoping central tube members, a plurality of casings, each comprising fixed and telescoping members; said casings being offset from and parallel to the central tube members, and means connecting the fixed central tube members with the fixed members of

the casings and the telescoping tube member with the telescoping members of the casings.

2. In a chandelier, the combination of 5 fixed and telescoping central tube members, a plurality of casings, each comprising fixed and telescoping members; said casings being offset from and parallel to the central tube members, and means connecting the 10 fixed central tube members with the fixed members of the casings, and the telescoping tube member with the telescoping members of the casings, there being a plurality of 15 such connections between each fixed casing member and the fixed tube member, spaced apart longitudinally of the tube member and thereby fixing said parts against relative torsional displacement.

3. In a chandelier, the combination of 20 fixed and telescoping central tube members, a plurality of casings, each comprising fixed and telescoping members; said casings being offset from and parallel to the central tube members, and means connecting the fixed 25 central tube members with the fixed members of the casings, and the telescoping tube member with the telescoping members of the casings, there being a plurality of such 30 connections between each fixed casing member and the fixed tube member, spaced apart longitudinally of the tube member and thereby fixing said parts against relative torsional displacement, and the connections 35 between the telescoping tube member and the telescoping casing members comprising tubular chandelier arms communicating with the interior of the telescoping central tube member.

4. In a chandelier, the combination of

fixed and telescoping central tube members, 40 a plurality of casings, each comprising fixed and telescoping members, said casings being offset from and parallel to the central tube members, and means connecting the fixed central tube members with the fixed members 45 of the casings and the telescoping tube member with the telescoping members of the casing, and telescoping electric conductors each comprising a fixed and a telescoping member and located within and connected to the fixed and telescoping members 50 of the respective casings.

5. In a chandelier, the combination of 55 fixed and telescoping central tube members, a plurality of casings, each comprising fixed and telescoping members; said casings being offset from and parallel to the central tube members, and means connecting the fixed 60 central tube members with the fixed members of the casings and the telescoping tube member with the telescoping members of the casings, and a friction grip carried by one member of each conductor casing and bearing against the other member thereof.

6. In combination with a chandelier comprising telescoping gas tubes, a plurality of telescoping conductor casings, offset from and parallel to the said gas tubes, and a pair of lamp brackets mounted on one of the said gas tubes, and constructed with means for 70 supporting one member of each of said conductor casings.

The foregoing specification signed at Elkhart Ind. this 28th day of May, 1913.

WARREN POTTS.
